DESIGN FOR A COMBINED SODA WATER FOUNTAIN AND CABINET

Martin C. Schwab, Hales Corners, and Jesse Seymour Berner, Milwaukee, Wis.

Application July 26, 1935, Serial No. 57,814

Term of patent 7 years

To all whom it may concern:

Be it known that we, Martin C. Schwab and Jesse Seymour Berner, of Hales Corners and Milwaukee, respectively, in the county of Milwaukee and State of Wisconsin, have invented a new, original, and ornamental Design for a Combined Soda Water Fountain and Cabinet, of which the following is a specification, reference being had to the accompanying drawing, forming part thereof.

Figure 1 is a front perspective view of the combined soda water fountain and cabinet, showing our design; and

Figure 2 is a rear perspective view thereof.

The essential feature of the design resides in the fountain portion, as best shown in Figure 1.

We claim:

The ornamental design for a combined soda water fountain and cabinet, as shown and described.

MARTIN C. SCHWAB.
JESSE SEYMOUR BERNER.
